UNITED STATES PATENT OFFICE.

ROBERT CARL RAHM, OF WYOMISSING, PENNSYLVANIA, ASSIGNOR TO BERKS ENGINEERING CO. INC., OF READING, PENNSYLVANIA, A CORPORATION OF PENNSYLVANIA.

DYEING MACHINE.

Application filed February 14, 1925. Serial No. 9,125.

This invention relates particularly to dyeing machinery which employs a fabric receptacle pivotally movable into and out of the liquid tank in connection with an agitator pivotally movable into and out of said receptacle; and is an improvement on the type of machine set forth in Patent No. 1,485,884 of March 4, 1924.

The main object of this invention is to render the agitator adjustable with respect to the level of the dye liquor within the tank so that dye liquor in excess of the proper amount for a given amount of goods to be dyed will not be required for proper functioning of the machine.

Other objects of this invention are to improve the driving mechanism for the agitator paddle and also to improve the gearing for swinging the fabric receptacle into and out of the liquid tank.

With these and other objects in view as will be apparent as the description proceeds, reference will be had to the accompanying drawings forming a part of this specification and wherein like numerals of reference designate corresponding parts throughout the several views, in which:

Fig. 1 is a front elevation of a preferred form of the invention with parts broken away and shown in section,

Fig. 2 is a similar view of a fragment thereof, with parts in another position,

Fig. 3 is a vertical sectional view taken substantially on line 3—3 of Fig. 1, but the gearing at the right side being in section on the line 3a—3a.

In the drawings, reference numeral 2 designates the frame of the machine, and fixed within the frame is a liquid tank 3, and within the tank is located the perforated fabric receptacle 4. The fabric receptacle 4 is designed to be moved into and out of the tank 3 by being swung upon its pivot 5 which is in the nature of a rock shaft to which the receptacle 4 is fixed and to the outer ends of which are fixed quadrant arms 6 which have gear teeth 7 that mesh at times with teeth of main gear wheels 8 to cause actuation of said quadrants 6 and swinging of the fabric receptacle 4 into and out of the liquid tank 3.

The gear wheels 8 are journaled on bearings 9, mounted by arms or brackets 10 upon the upper edge of the tank frame 2. Eccen-

trically journaled in the bearings 9 is a transverse shaft 12 which has a rocking movement and to which are fixed the agitator carrying arms 14, the same and their associated parts on one side of the rock shaft 12 being counterbalanced by arms 15 and weights 16 on the other side of said rock shaft 12. When the teeth of the gear wheels 8 and the quadrants 6 are enmeshed and the fabric receptacle raised, its weight is counterbalanced by the weights 17 hung from cables 18 passed over or around pulleys or drums 19 on the hubs of the main gear wheels 8 and the ends of said cables being suitably secured to said drums.

One of the carrying arms 14 has its free end extending downwardly at an angle to its main part, while the other carrying arm 14 has a similar, though somewhat modified, downwardly extending free end, the modification consisting of forming such downwardly extending end in the nature of a gear casing 20, though obviously both of said arms 14 could be alike and the gear casing 20 attached as a separate element. Journaled across the lower free ends of the downwardly extending portions of the arms 14, or the arm 14 and gear casing 20 when one of the arms takes the form of a gear casing, is a shaft 21 to which the rotary agitator 22 of well known form is suitably fixed, and on the outer end of this shaft 21 is a gear 24 which may be directly meshed with a gear 25, or as illustrated in the drawings, indirectly meshed with said gear 25 through an intermediate chain of gearing, and all of said gears and gearing being housed within the same casing 20. This casing should be substantially liquid tight to protect the inclosed gearing from the action of the dye liquor as well as to protect the dye liquor from contamination by grease from the gearing.

The said gear 25 is suitably keyed to a cross shaft 26 journaled in the carrying arms 14, and to the outer end of this shaft 26 is suitably keyed a sprocket wheel 27, a sprocket chain 28 driving the same from one part of a double sprocket wheel 29 which is journaled on the free end of the rock shaft 12, and this double sprocket wheel 29 being in turn driven by a sprocket chain 30 passing around the other part of said double sprocket and around a sprocket wheel 31.

loose on an intermediate drive shaft 32. This drive shaft 32 is also equipped with pinions 33 enmeshed with the main gear wheels 8 for driving the same. The loose 5 sprocket 31 is a counterpart of a worm wheel 34 also loose on said shaft 32 and rotates therewith. Keyed to said shaft 32 is a second worm wheel 35 by means of which said shaft is driven. The drive 10 mechanism is otherwise substantially the same as in Patent No. 1,485,884 and briefly consists of a suitable motor 36, its shaft 37, countershaft 38, pinions 39-40 keyed to shaft 38, pinions 41-42 keyed to shaft 37, sliding key 43 to interlock with either of the pinions 39-40 or to disconnect entirely 15 from both, and worms 44 on the shafts 37-38 for driving the worm wheels 34-35. A hand lever, or a system thereof, 45 shifts the sliding key 43, and in some instances 20 automatic stop and reversing mechanism common to machines of this general type may be provided.

The main gear wheels 8 are provided with 25 projections 50 having spaced flanges 51 and 52 of different radial extent and adapted to engage and disengage a lateral projection 53 on each of the agitator carrying arms 14, as in Patent No. 1,485,884 above mentioned. 30 The main gear wheels are also provided with a large projecting tooth 60 extending beyond the teeth thereof, and a similar tooth 61 is provided on the upper end of the teeth range 35 of the quadrant arms 6. It will be observed that for a distance from the tooth 61 there are no teeth 7 on the quadrant arms 6 and that this permits rotation of the main gear wheels 8 to lift the agitator carrying arms 14 a distance without elevating the 40 fabric receptacle 4, but that as soon as the teeth 60 and 61 become engaged, the teeth of the main gear wheels 8 engage with those of the quadrant arms 6 and elevation of the fabric receptacle 4 begins.

45 In operation, assuming that the fabric receptacle is lowered into the liquid tank and the mechanism has been operated to lower the agitator 22 into the said receptacle,—when the agitator is at the desired level according to the level of the dye liquor, the lowering mechanism is stopped and the agitator paddle operated. In this position, the teeth 60 of the main gear wheels 8 will be somewhere between the Fig. 1 and Fig. 2 positions and 50 the gear teeth of the gear wheels 8 out of mesh with the teeth 7 of the quadrant arms. When it is desired to remove the goods, the hand lever 45 is shifted to stop the rotation of the agitator and to cause rotation of the main gear wheels in the same manner as in said Patent No. 1,485,884, and as the gear 55 wheels 8 rotate, the flanges 51 engaging with the projections 53 of the carrying arms 14, cause elevation of the agitator. As this elevation continues and at the point where the

agitator paddle 22 would be working at the highest possible liquid level, the large tooth 60 of each gear wheel 8 comes into engagement with the large tooth 61 of each quadrant arm 6, and as the elevation of the agitator carrying arms 14 and their associated mechanism continues, the teeth of the main gear wheels 8 enter into mesh with the teeth 7 of the quadrant arms 6 and the elevation of the fabric receptacle then begins. When 70 the agitator carrying arms 14 reach the vertical or substantially the vertical position, the eccentricity of the bearings has caused flanges 51 of each gear wheel 8 to clear the projections 53 of the carrying arms, and the 75 gear wheels 8 are permitted to continue their rotation without further action on the agitator carrying arms, but continuing their action upon the quadrant arms 6 until the fabric receptacle has been raised the desired 80 degree, when by appropriate manipulation of the reversing mechanism, by sliding key 43 as in said patent, the main gear wheels 8 reverse their direction of rotation. The flanges 52 of the gear wheels again encounter 85 projections 53 of the carrying arms 14 and return the agitator to a position within the tank, and at the same time gear wheels 8 being still enmeshed with the teeth of the quadrant arms 6, continue to return the fabric 90 receptacle to its position within the tank. When the fabric receptacle has been fully 95 lowered into the tank, teeth 7 of the quadrant arms 6 leave the gear wheels 8 and the latter continue rotation until such time as the key 43 is shifted to stop rotation of the gear wheels 8. This shifting of the key 43 takes place when the agitator paddle 22 has reached the point according to the level 100 of the dye liquor at which it is desired the same should operate, and when that point is reached, by properly moving said key 43, the agitator paddle may be rotated to effect proper agitation of the dye liquor during 105 dyeing. It is to be pointed out that when the teeth 7 of the quadrant arms 6 leave those of the gear wheels 8, sudden dropping of the quadrant arms 6 and the fabric receptacle is prevented by the large teeth 60-61 having 110 become engaged, so that after the small teeth have acted in the lowering operation of the quadrant arms, the large teeth 60-61 take up the work of lowering, and after the fabric receptacle is fully lowered, the mechanism may be then stopped to prevent further lowering of the agitator, or the gear 115 wheels 8 may be rotated farther to effect further lowering of the agitator, during which latter, the tooth 60 of each gear wheel 8 merely moves away from the tooth 61 of the quadrant arms.

Having fully described the invention, what is claimed as new and useful and desired to be secured by Letters Patent is:—

1. The combination with a liquid tank, a 130

5 pivoted fabric receptacle mounted to swing into or out of said tank, and an agitator pivotally mounted to swing into and out of said receptacle, of means adapted to swing said receptacle and agitator jointly and to swing the agitator independently.

2. The combination with a liquid tank, a pivoted fabric receptacle mounted to swing into or out of said tank, and an agitator 10 pivotally mounted to swing into and out of said receptacle, of means adapted to swing said receptacle and agitator jointly for a distance and beyond that distance to swing the agitator independently.

15 3. The combination with a liquid tank, a pivoted fabric receptacle mounted to swing into and out of said tank, and an agitator pivotally mounted to swing into and out of said receptacle, of means for swinging the 20 receptacle and agitator jointly into and out of said tank, and means for independently swinging the agitator farther into the receptacle after the receptacle has completed its movement into the receptacle.

25 4. The combination with a liquid tank, a pivoted fabric receptacle mounted to swing into and out of said tank, and an agitator pivotally mounted to swing into and out of said receptacle, of means for swinging the 30 receptacle and agitator jointly for a part of the distance and the agitator independently for the remainder of the distance into the receptacle, and for swinging the agitator independently for a part of the distance and 35 the receptacle and agitator jointly for the remainder of the distance from within the receptacle.

40 5. The combination with a liquid tank, a pivoted fabric receptacle mounted to swing into and out of said tank, and an agitator pivotally mounted to swing into and out of said receptacle; of means adapted to swing 45 said receptacle and agitator jointly and to swing the agitator independently, and means for actuating the agitator at any point in its range of independent swing.

50 6. The combination with a liquid tank, a pivoted fabric receptacle mounted to swing into and out of said tank, and an agitator pivotally mounted to swing into and out of said receptacle; of means adapted to swing 55 said receptacle and agitator jointly and to swing the agitator independently, and means for arresting swinging movement of the agitator at any point in its range of independent swing.

60 7. The combination with a liquid tank, a pivoted fabric receptacle mounted to swing into and out of said tank, and an agitator pivotally mounted to swing into and out of said receptacle; of means adapted to swing 65 said receptacle and agitator jointly and to swing the agitator independently, and means for arresting swinging movement of the agitator at any point in its range of independent

swing, and means for actuating said agitator at any such point of arrest.

8. The combination with a liquid tank, a pivoted fabric receptacle mounted to swing into and out of said tank, an agitator adapted to 70 swing into and out of the receptacle; of means for swinging the agitator and receptacle together, and means for varying the working depth of the agitator in said receptacle.

75 9. The combination with a liquid tank, of a fabric receptacle mounted to swing into and out of said tank, an agitator mounted to swing into and out of said receptacle, a gear element having an interruption in its gear teeth and connected with the fabric receptacle for swinging the same, said receptacle and agitator swinging together when the teeth of said gear elements are intermeshed, and the agitator swinging independently of 80 the fabric receptacle when one of the gear elements is operating in the interrupted part of the toothed portion of the other gear element.

85 10. The combination with a liquid tank, a pivoted fabric receptacle mounted to swing into and out of said tank, an agitator mounted to swing into and out of the receptacle, a gear element having an interruption in its gear 90 teeth and connected with the fabric receptacle for swinging the same, said receptacle and agitator swinging together when the teeth of said gear elements are intermeshed on either side of said interruption, and the agitator swinging independently of the fabric 95 receptacle when one of the gear elements is operating in the interrupted part of the toothed portion of the other gear element.

100 11. In a device of the character described, a liquid tank, a fabric receptacle movable into and out of the same, a toothed quadrant arm for so moving the fabric receptacle, an agitator movable into and out of the fabric receptacle, a member for so moving the agitator, said member having teeth which are 105 enmeshed with those of the quadrant arm only when the fabric receptacle is out of working position, and means for moving the fabric receptacle out of working position to effect enmeshing of said teeth.

110 12. In a device of the character described, a liquid tank, a fabric receptacle movable into and out of the same, a toothed quadrant arm for so moving the fabric receptacle, an agitator movable into and out of the fabric receptacle, a gear member for so moving the agitator, the tooth of said gear member 115 enmeshing with those of the quadrant arm only when the fabric receptacle is out of working position, and means on said quadrant arm and gear member which interengage to effect enmeshing of said teeth.

120 13. In a device of the character described, a liquid tank, a fabric receptacle movable 125

into and out of the same, a toothed quadrant arm for so moving the fabric receptacle, an agitator movable into and out of the fabric receptacle, a toothed member for so moving the agitator, the teeth of said quadrant arm and member enmeshing only when the fabric receptacle is out of working position, and supplemental teeth on said quadrant arm and member which interengage and effect enmeshing of said first mentioned teeth.

14. The combination with a liquid tank, a fabric receptacle mounted to swing into and out of said tank, and a rotary agitator

adapted to swing into and out of the receptacle; of a pivotally mounted agitator carrying arm having a hollow free portion forming an agitator bearing and drive-gear casing.

15. The combination with a liquid tank, of an agitator of less width than said tank pivotally mounted to swing completely into and out of said tank to vary its working depth, and means for actuating the agitator at any point in its range of swing, movable with said agitator into said tank.

25
In testimony whereof I affix my signature.

ROBERT CARL RAHM.
